UNITED STATES PATENT OFFICE.

EGBERT MOXHAM, OF WILMINGTON, DELAWARE.

COLLAPSIBLE MANDREL.

SPECIFICATION forming part of Letters Patent No. 766,459, dated August 2, 1904.

Application filed March 1, 1904. Serial No. 198,032. (No model.)

To all whom it may concern:

Be it known that I, EGBERT MOXHAM, a citizen of the United States, residing at Wilmington, county of Newcastle, and State of Delaware, have invented a new and useful Improvement in Collapsible Mandrels, of which the following is a full, clear, and exact description; reference being had to the accompanying drawings, which form a part of this specification.

My invention relates to collapsible mandrels, and while more especially adapted for use in a machine for the manufacture of tubes from pulp, as a winding or press roller for receiving the layers of pulp collected from the pulp in the vat, is adapted for any purpose for which a collapsible mandrel may be employed.

The object of the invention is to so construct the mandrel that it may be contracted radially to facilitate the removal endwise of the tubes or tubular sections of pulp or other material formed thereon, while in operation it may be expanded radially to the full diameter of the tube or tubular sections to be formed. The object of the invention is also to so construct the operative parts that the roll may be quickly collapsed and expanded and yet will be held firmly in its expanded position.

The invention consists of the general and specific construction and arrangement of parts, as hereinafter described and claimed.

In the drawings, Figure 1 is a side view of the roll. Fig. 2 is a horizontal section taken longitudinally through the roll when the latter is expanded. Fig. 3 is a vertical section taken longitudinally through the roll when the latter is contracted. Fig. 4 is an end view looking toward the left-hand end of Fig. 2. Fig. 5 is an end view looking toward the right-hand end of Fig. 2. Fig. 6 is an end view looking toward the right-hand end of Fig. 3.

45 *a b c d* are the four sections of the periphery of the roll. Each section is tapered in width from one end to the other. The oppositely-located sections *a* and *b* are each widest at their right-hand ends and narrowest at 50 their left-hand ends and are arranged alternately with respect to the oppositely-located

sections *c* and *d*, which are each widest at their left-hand ends and narrowest at their right-hand ends.

To expand the roll, the pair of sections *a* and *b* and the pair of sections *c* and *d* are moved outwardly and in opposite directions longitudinally, sections *a* and *b* being moved to the left and sections *c* and *d* to the right. When in such position, all the sections fit together as exactly as may be—that is, the peripheral portions and end portions of all the sections coincide to form a true circular roll having a smooth periphery, as shown in Figs. 2, 4, and 5.

To contract the roll, the two pairs of sections are moved inwardly and in longitudinal directions opposite to those in which they are moved to expand the roll, sections *a* and *b* being moved to the right and sections *c* and *d* to the left. When in such position, the sections are out of alinement, both around the periphery and at the ends, as shown in Figs. 3 and 5.

To give to the roll-sections the movements just described the following mechanism is provided: *e* is a hollow shaft extending through the longitudinal center of the roll. *f f*, &c., and *g g*, &c., are two series of lugs on the outside of shaft *e*. *h h*, &c., are a series of lugs on the inside of sections *a* and *b*. *i i*, &c., are a series of lugs on the inside of sections *c* and *d*. *k k*, &c., are a series of links connecting lugs *f* with lugs *h*. *l l*, &c., are a series of links connecting lugs *g* with lugs *i*. *m* is a rotatable sleeve on the left-hand end of shaft *e*, said sleeve being provided with an exteriorly-screw-threaded portion on each side of its center, one portion having a right-hand screw and the other portion a left-hand screw. The threaded sleeve *m* is confined between collars *n n* to prevent it from moving longitudinally. *o* and *p* are nuts on the threaded sleeve *m*.

q q are a pair of levers pivoted at one end to the nut *o* and at the other end respectively to the left-hand lug *h* on section *a* and the left-hand lug *h* on section *b*. *r r* are a pair of levers pivoted at one end to the nut *p* and at the other end respectively to the left-hand lug *i* on section *c* and the left-hand lug *i* on section *d*.

It will be understood from the foregoing description that when the threaded sleeve *m* is rotated the lugs *o* and *p* will be moved away from or toward each other and the two 5 pairs of roll-sections *a b* and *c d* moved in opposite directions and either outwardly or inwardly, dependent upon whether the lugs on the roll-sections move toward or away from the radial plane in which the corresponding lugs on the shaft *e* are located.

More specifically, the arrangement is such, as may be seen by reference to Figs. 2 and 3, that when the threaded sleeve *m* is turned so as to cause the nuts *o* and *p* to recede from 15 each other the levers *q* are drawn to the left and the lugs *h* moved to the left into a position in radial alinement with the respective lugs *f* on the shaft *e*, thereby causing sections *a* and *b* to move to the left and at the 20 same time outwardly. Similarly the levers *r* are simultaneously drawn to the right and the lugs *i* moved to the right into a position in radial alinement with the respective lugs *g* on the shaft *e*, thereby causing sections *c* and 25 *d* to move to the right and at the same time outwardly.

The described outward and longitudinal movement of the sections is arrested by the contact of the nut *o* with the annular flanged 30 end of sleeve *m* and of the nut *p* with the inner collar *n*. To more certainly limit this described movement of the sections, arms *s* are provided on one or more of the links *k* and *l*, which arms contact with the shaft when 35 the links are brought to a radial position, and thus arrest the longitudinal movement of the sections independently of the contact of the nuts *o* and *p* with the collars *n*.

When the threaded sleeve *m* is turned so as 40 to cause the nuts *o* and *p* to approach each other, the levers *q* and connected sections *a* and *b* are moved to the right and by reason of the link connection with the shaft *e* are at the same time moved inwardly. Similarly 45 the levers *r* and connected sections *c* and *d* are moved to the left and by reason of the link connections with the shaft *e* are at the same time moved inwardly.

The described inward and longitudinal 50 movement of the sections is necessarily arrested by the nuts *o* and *p* contacting with each other on reaching the ends of their respective threads, although it will be understood that it is unnecessary to arrest the inward movement of the sections at any precise point.

In order to hold the sections rigidly in position when the roll is expanded, the following mechanism is provided: *t* is a shaft extending through the longitudinal center of the roll and the hollow shaft *e*. *u u* are screw-threads at opposite ends of the shaft, one thread being a right-hand screw and the other a left-hand screw. *v v* are nuts on the right and 65 left hand screw-threads *u u*, respectively.

w w, &c., are radial arms extending from nuts *v v* out through slots *x x* in the hollow shaft *e*. *y y* are circular heads secured to the arms *w*, radiating from the nuts *v v*, respectively. *z z*, &c., are ring-sections secured to the inside of each of the roll-sections *a, b, c*, and *d* at each end of the roll.

The ring-sections are in such position that when the roll-sections are expanded, as before described, the ring-sections at each end will 75 exactly coincide, forming a true unbroken ring extending entirely around the inner side of each end of the roll.

The inner faces of the ring-sections *z* and the outer faces of the heads *y* are each beveled, 80 as shown, and the diameters of the heads are such that when the heads are moved longitudinally into radial alinement with the ring-sections when the roll-sections are expanded they will fit nicely within the ring-sections, and 85 thereby maintain the roll in its expanded condition. The beveled faces of the heads and ring-sections permit a ready engagement between the same and at the same time allow the degree of pressure of the heads against 90 the ring-sections to be regulated at will.

The heads are moved longitudinally into their operative positions by rotating the shaft *t*, this being accomplished by any desired means, as by a wrench applied to the squared 95 end *y* of shaft *t*. The slots *x* in the hollow shaft *t* permit the described longitudinal movement of the radiating arms *w*.

It will be understood from the foregoing description that to expand the roll the sleeve *m* 100 is first turned until the roll-sections are brought into peripheral alinement, after which the shaft *t* is turned to bring the heads *y* within and in bearing contact with the ring-sections *z*.

To contract the roll, the shaft *t* is first turned to retract the heads *y*, after which the sleeve *m* is turned to draw in the roll-sections. The heads *y* are suitably slotted, as at *y'*, to permit the levers *q* and *r* to extend through them.

A bearing *t'*, within the hollow shaft *e*, is provided for the shaft *t*.

Any desired number of roll-sections may be provided.

Having now fully described my invention, 115 what I claim, and desire to protect by Letters Patent, is—

1. A collapsible mandrel consisting of a plurality of longitudinally-extending roll-sections tapering in width, alternate sections being inversely arranged, and means to move the alternate sections in either direction longitudinally, and simultaneously in opposite directions, and either outwardly or inwardly simultaneously dependent upon the direction 125 of longitudinal movement, thereby contracting or expanding the roll as a whole.

2. A collapsible mandrel consisting of a plurality of longitudinally-extending roll-sections tapered in width, alternate sections be- 130

- ing inversely arranged, means to move said alternate sections in either direction longitudinally and reversely to each other, and devices compelling the movement of said sections inwardly or outwardly determinate upon the directions in which they are moved longitudinally.
3. A collapsible mandrel consisting of a plurality of longitudinally-extending roll-sections, each section being tapered in width, the sections being so arranged that the wide and narrow ends of the several roll-sections are arranged alternately at each end of the roll, and means adapted to move said roll-sections simultaneously outwardly and longitudinally to expand the roll and simultaneously inwardly and longitudinally to contract the roll.
4. A collapsible mandrel consisting of a plurality of longitudinally-extending roll-sections tapering in width, alternate sections being inversely arranged, and means to move the alternate sections in either direction longitudinally, and simultaneously in opposite directions and either outwardly or inwardly simultaneously dependent upon the direction of longitudinal movement, and a device adapted to hold the sections rigidly in their outer positions.
5. A collapsible mandrel consisting of a plurality of longitudinally-extending roll-sections tapering in width, alternate sections being inversely arranged, and means to move the alternate sections in either direction longitudinally, and simultaneously in opposite directions, and either outwardly or inwardly simultaneously dependent upon the direction of longitudinal movement, thereby contracting or expanding the roll as a whole, a device to hold the sections rigidly in their outer positions, and a stop to limit the movement of the sections in their expanding movement.
6. A collapsible mandrel consisting of a plurality of longitudinally-extending roll-sections, a shaft extending along the axis of the roll, means to simultaneously move one or more sections longitudinally in one direction and one or more sections longitudinally in the opposite direction, and a series of links connecting said shaft and roll-sections to cause said sections to move toward or from the roll-axis in their longitudinal movement.
7. A collapsible mandrel consisting of a plurality of longitudinally-extending roll-sections, a hollow shaft extending through the roll, connections between said shaft and roll-sections whereby said sections are given a simultaneous longitudinal and outward movement, a shaft extending through said hollow shaft, a head within the roll, connections, extending through said hollow shaft, between said inner shaft and head, and adapted to be operated by said shaft to cause said head to engage said sections and maintain them in their outer positions.
8. A collapsible mandrel consisting of a plurality of longitudinally-extending roll-sections, a hollow shaft extending through the roll and provided with longitudinally-extending slots, means to move said sections longitudinally, a series of links connecting said shaft and roll-sections to cause said sections to move toward or from the roll-axis in their longitudinal movement, a shaft extending through the hollow shaft, a head within the roll, connections, extending through the slots in said hollow shaft, between said inner shaft and head and adapted to be operated by said shaft to move said head longitudinally and thereby cause said head to engage said sections and maintain them in their outer positions.
9. A collapsible mandrel consisting of a plurality of longitudinally-extending roll-sections, a shaft extending along the axis of the roll, a sleeve on said shaft, having right and left hand screw-threads, a nut on each screw-thread, levers respectively connecting said nuts and roll-sections, whereby the turning of said sleeve imparts a longitudinal movement in one direction to the section or sections connected with one nut, and a longitudinal movement in the other direction to the section or sections connected with the other nut, and connections between said shaft and roll-sections adapted to compel the outward or inward movement of said roll-sections dependent upon the direction in which said sleeve is turned.
10. A collapsible mandrel consisting of a plurality of longitudinally-extending roll-sections, a shaft extending along the axis of the roll, a threaded sleeve on said shaft, a nut on said sleeve, levers connecting said nut and roll-sections, whereby the turning of said sleeve imparts a longitudinal movement to said sections, links connecting said shaft and roll-sections adapted to compel the outward or inward movement of said roll-sections dependent upon the longitudinal direction in which they are moved, and a head to hold said sections in their outer or expanded positions.
11. A collapsible mandrel consisting of a plurality of longitudinally-extending roll-sections, a hollow shaft extending through the roll provided with longitudinally-extending slots, a threaded sleeve on said shaft, a nut on said sleeve, levers connecting said nut and roll-sections, links connecting said hollow shaft and roll-sections, a threaded shaft extending through the hollow shaft, a nut on said threaded shaft, a head within the roll, and connections, extending through the slots in the hollow shaft, between the last-named nut and the head.
12. A collapsible mandrel consisting of a plurality of longitudinally-extending roll-sections tapering in width, alternate sections being inversely arranged, a sleeve having right and left hand screw-threads, a nut on each screw-thread, and levers connecting the nuts.

with the inversely-arranged roll-sections respectively,

13. A collapsible mandrel consisting of a plurality of longitudinally-extending roll-sections tapering in width, alternate sections being inversely arranged, means to move the alternate sections in either direction longitudinally and simultaneously in opposite directions, a shaft within the roll, and links connecting the shaft and the roll-sections to compel the latter to move simultaneously outwardly or inwardly in their simultaneous longitudinal movement.

14. A collapsible mandrel consisting of a plurality of longitudinally-extending roll-sections, means to move said sections outwardly, a ring-section on each roll-section, a head within the roll, and means to move said head longitudinally into engagement with the ring-sections.

15. A collapsible mandrel consisting of a plurality of longitudinally-extending roll-sections, means to move said sections outwardly, a ring-section on each roll-section, having a beveled inner face, a head within the roll having a beveled outer face, a threaded shaft, a nut thereon, and arms connecting said nut and head.

16. A collapsible mandrel consisting of a plurality of longitudinally-extending roll-sections tapering in width, alternate sections being inversely arranged, a shaft, a rotatable sleeve thereon having right and left hand screw-threads, a nut on each screw-thread, levers connecting the nuts with the inversely-arranged roll-sections respectively, and links connecting the shaft and roll-sections.

17. A collapsible mandrel consisting of a plurality of longitudinally-extending roll-sections tapering in width, alternate sections being inversely arranged, a hollow shaft, a rotatable sleeve thereon having right and left hand screw-threads, a nut on each screw-thread, levers connecting the nuts with the inversely-arranged roll-sections respectively, and links connecting the shaft and roll-sections.

18. A collapsible mandrel consisting of a plurality of longitudinally-extending roll-sections tapering in width, alternate sections being inversely arranged, a hollow shaft, a rotatable sleeve thereon having right and left hand screw-threads, a nut on each screw-thread, levers connecting the nuts with the inversely-arranged roll-sections respectively, and links connecting the hollow shaft and roll-sections, a threaded shaft extending through the hollow shaft, a nut on the threaded shaft, a head within the roll adapted to engage the roll-sections when expanded, and arms connecting the head and nut, said arms extending through the hollow shaft.

In testimony of which invention I have hereunto set my hand, at Wilmington, on this 25th day of February, 1904.

EGBERT MOXHAM.
